ALVIE C. CRIMMEL AND HENRY H. CRIMMEL, OF HARTFORD CITY, INDIANA

GLASS DEFROSTING TRAY FOR MECHANICAL REFRIGERATORS

Application filed June 11, 1932. Serial No. 616,630.

This invention relates to a tray construction for mechanical refrigerators.

The chief object of this construction is to provide tray means for positioning between a shelf or support within a mechanical refrigerator and the condenser thereof, so that the tray means is adapted to catch the drippings when defrosting.

Another object of the invention is to provide tray means whereby when in defrosting the ice sheet upon the condenser and the like becomes detached and falls, the tray is adapted to catch the same and permit the ice sheet to slide inwardly into and lie upon the bottom of the tray means instead of being caught between the side wall of the tray and the condenser and topple out of the tray or the overhanging sheet portion melt and drip below.

The advantages of a ribbed bottom tray are fully set forth in the co-pending application Serial No. 543,642, filed June 11, 1931, of which this application is a continuation in part.

The invention disclosed herein is illustrated as embodying a plurality of associated trays for operative association with a multiple size single unit condenser. When the condenser unit is of relatively narrow width, of course, only a single tray need be employed and the single tray need not necessarily be provided with the lip means, illustrated, described and claimed per se in the before mentioned application.

Each tray in the present invention is illustrated as being provided upon a plurality of sides with rim means and one of said sides has the rim means omitted therefrom.

The full nature of the invention will be understood from the accompanying drawing and the following description and claims:—

In the drawing, Fig. 1 is an elevational view of a mechanical refrigerator of the conventional type, showing a pair of trays positioned beneath the condenser and in drip collecting or defrosting relation.

Fig. 2 is a top plan view of one of the pair of trays.

Fig. 3 is an end elevation thereof.

Fig. 4 is a transverse sectional view taken

on line 4—4 of Fig. 2, and in the direction of the arrows.

Fig. 5 is a view similar to Fig. 2 and of a modified form of the invention.

Fig. 6 is a view similar to Figs. 2 and 5, and of a further modified form of the invention.

In the drawing, 10 indicates a mechanical refrigerator, the refrigerating compartment being indicated by the numeral 11 and including various shelves and supports 12, access to the compartment being had through the door 13. Positioned in the refrigerator, in the usual manner, is the usual condenser, or cooling coil 14, which, in the present disclosure, is illustrated as having considerable width. Positioned therebeneath in the present disclosure, is a pair of trays, the same being operatively associated together for catching the drip from the cooling coil and the ice that is dropped from the outside thereof when the unit is defrosted.

In Figs. 2, 3 and 4, one form of tray is illustrated. In said figures, 15 indicates the bottom of one of the trays, the same being slightly elevated above the foot or lower rim portion 16. Extending upwardly from the bottom and integral with the bottom, are the side walls 17 which are inclined slightly outwardly. Herein the tray is shown rectangular with the inner side of the side walls inclined downwardly and inwardly for drainage toward the bottom of the tray. Each side wall, except one, is provided with an upper rim 18 and the same extends outwardly an appreciable distance from the side wall 17.

Adjacent the ends of the rim 18 and the end of the side wall 17, not provided with a rim, the terminating ends are cut away, as indicated at 19, and this portion serves as a lip, or pouring spout, when the tray is to be emptied of any liquid therein. The rim 18 of the side wall opposite the rimless side which terminates in the top edge 20, is arranged to overlap the rimless side 17 and the top edge 20 of an adjacent tray when the trays are positioned side by side. The upper surface of the bottom 15 of the tray is provided with a plurality of spaced and parallel ribs 21, which, in the present form of the in-

vention—see Figs. 2, 3 and 4, extend from one side wall toward the other. Herein the ribs 21 extend from opposite side walls toward the other wall but terminating short of meeting engagement, although they are longitudinally aligned. Likewise, the spaces between the longitudinally aligned ribs are not arranged in transverse alignment, but are staggered, as shown clearly in Fig. 2.

10 The ribs provided upon the bottom 15, permit the air to circulate around the bottom and between the ribs, and, therefore, around and beneath any articles placed in the tray when the tray is positioned, as shown in Fig. 1, 15 which is a semi-freezing zone.

The tray is preferably made of glass, since this is the cheapest vitreous product available and may be produced commercially in large quantities by a molding process. As set 20 forth in the co-pending application, a plurality of associated trays is provided, because glass trays in large sizes would warp if made in as thin a thickness as the smaller trays are made. If a large glass tray, the equivalent 25 of a plurality of trays of smaller size were made, would not warp, the result would, of necessity, be a relatively thick and heavy tray which would cost more than the two trays, in the matter of material and finishing, and 30 which would have the added objection of having more weight than the housewife could conveniently handle.

In Fig. 5, there is illustrated a modified form of the invention, wherein similar parts 25 are indicated by the numerals of the one hundred series, and as illustrated in this form of the invention, the last rib, herein indicated by the numeral 131, adjacent the mouth 119, is formed with a curvature 132 which assists 30 in the drainage of the liquid and yet, it functions in the same capacity as the ribs 121.

In Fig. 6, there is illustrated a modified form of the invention, wherein the ribbing at the corners is not comprised of parallel 45 ribs but which are inclined, as at 231, and these ribs extend towards the center of the tray but terminate short of meeting engagement. In all three forms of the invention, the ribbing is shown integral with the bottom of the tray and extends from one side 50 wall towards the other but terminates short

of the other side wall and when a pair of ribs are longitudinally aligned, the aligned ribs terminate short of each other. The spaces between the longitudinally aligned ribs, as illustrated, are not in transverse 70 alignment. While the ribbing is illustrated as being parallel to the short side of the tray, it may extend parallel to the long side of the tray as disclosed in the co-pending application. 75

The invention claimed is:—

1. An integral vitreous tray including a bottom, peripherally enveloping side walls, and a plurality of spaced and parallel upstanding ribs upon the upper surface of said bottom and extending from each of a pair of side walls toward the other wall, adjacent ribs being of unequal length, the ribs extending from opposite side walls being longitudinally aligned and terminating short of meeting engagement, each longitudinally aligned pair forming a space therebetween, the adjacent spaces being offset from the others for circulation and prevention of sheet locking. 80

2. An integral vitreous tray of quadrilateral outline including a bottom, peripherally enveloping side walls, and a plurality of spaced and parallel upstanding ribs upon the upper surface of said bottom and extending from each of a pair of side walls toward the other wall, adjacent ribs being of unequal length, the ribs extending from opposite side walls being longitudinally aligned and terminating short of meeting engagement each longitudinally aligned pair forming a space therebetween, the adjacent spaces being offset from the others for circulation and prevention of sheet locking, and other ribs projecting inwardly and angularly 95 from each of the other side walls and arranged in spaced relation with respect to each other, and of dissimilar length relative to the adjacent last mentioned ribs and the adjacent first mentioned ribs for providing 100 spacing therebetween. 105

In witness whereof, we have hereunto affixed our signatures.
